Primary Examiner — Derrick E Holland(74) *Attorney, Agent, or Firm* — Thomas W. Tolpin; Tolpin & Partners, PC(57) **CLAIM**

The ornamental design for a tube for a shirt, as shown and described.

DESCRIPTION

FIG. 1 is a front view of a tube for a shirt showing my new design;

FIG. 2 is a rear view thereof;

FIG. 3 is a front view thereof, showing an alternate environment; and,

FIG. 4 is a rear view thereof.

A cloth shirt packed in a transparent cylindrical tube.

The top and bottom views thereof are circular caps.

The broken lines shown represent unclaimed subject matter and form no part of the claimed design.
